UNITED STATES PATENT OFFICE.

EARL SILAS WETMORE, OF COLLEGE SPRINGS, IOWA.

ELECTRIC MOTOR.

1,033,221.

Specification of Letters Patent. Patented July 23, 1912.

Application filed January 26, 1911. Serial No. 604,914.

To all whom it may concern:

Be it known that I, EARL SILAS WETMORE, of College Springs, in the county of Page and State of Iowa, have invented a new and useful Electric Motor; and I do hereby declare that the following is a full, clear, and exact description of the same.

In the drawings: Figure 1 is a complete side view of the motor showing the electrical connections, and the positions of the different parts. Fig. 2 is a fragmentary view of the ratchet wheel, and the ratchet operated by the reciprocating lever. Fig. 3 is a fragmentary view of the ratchet wheel and a second ratchet.

Referring now to the drawings, I have shown a motor 1 in the form of an electro-magnet. A reciprocating lever 2 is supported at the top of a standard 3 by means of an arbor 5, which passes through flanges like that shown at 4. Secured to the base 3 are the laterally extending arms 6 and 7, the former holding a screw 8 and the latter the screws 9 and 10. 8 and 9 are adapted to regulate the amount of reciprocating motion of the lever, and 10 to increase or decrease the tension of a coil spring 11 connected with the lever. A flat spring 12, a little longer than the two screws are apart that are used to regulate the amount of reciprocating motion of the lever, is fastened at its center, and directly between the two flanges supporting the lever, to the under side of said lever, so that the ends are in front of the points of the regulating screws.

On one end of the reciprocating lever, and directly in front of the electro-magnet poles, a piece of metal 13 is fastened, and is adapted to be attracted by said magnet. A pawl or ratchet 14 is on the other end of the reciprocating lever, and is adapted to fall into the notches 21 formed by the teeth on a ratchet wheel, the same being pressed against the wheel by a flat oblong spring 15, having one end fastened to the lever and the other pressing against the back of the ratchet, also another flat spring of about the same shape is fastened on the front side of the pawl at 16, and extends almost to the catch, and which is adapted to come in contact with the teeth of the wheel, and has its tension varied by a screw 17 extending through from the back of the pawl and forcing it away from the ratchet, the spring 16 and the catch 18 being insulated from that part of the pawl

which slides on the next tooth it is to engage.

In connection with the pawl is a ratchet wheel 19, having its angular shaped teeth 20 fastened to the electrical insulating substance on the periphery of the wheel, each tooth being electrically insulated from the one next to it, while concentric metal rings 22 and 23, are fastened to said wheel, and short electrical conductors 24 are used to connect every other tooth to one ring, and those remaining between those already connected to the other ring, making two complete circuits, each having half the teeth on the periphery of the wheel in its circuit, the wheel itself being mounted on a shaft 25, which is supported by bearings like 26 on each side of same. Another ratchet 27 is also in contact with the wheel 19, and is adapted to keep the wheel from turning the wrong way, also as an electrical conductor, and is placed so that when the other ratchet is in its normal position the electric circuit is complete; the current flowing from one side of the source of supply 35, switch 36 (when the latter is closed) through the electro-magnet coils, base 37, the standard 3, bar 2, to spring 16 on ratchet 17, and from spring through one of the electric circuits on the wheel to the other ratchet 27, then back to the source of supply. On top of said ratchet is a substantially V shaped spring 28, which has one leg fastened to the end of the ratchet, and is positioned so that the other leg comes in contact with the tooth in advance of the catch 29, and serves as an electrical conductor and a cushion for the ratchet to fall on as it drops over the point of the teeth, and at the base 32 of said ratchet is an oblong spring 30 for holding the ratchet against the teeth on the wheel.

When the circuit is complete through the motor as described above, the end of the reciprocating lever is drawn toward the magnets, causing ratchet 14 to be moved in the opposite direction, and turn the wheel 19, until the circuit is broken by ratchet 27 falling onto another tooth. Ratchet 14 is now drawn back one tooth, and the circuit is again complete through the other ring, causing the same action to take place as before, and the motor will continue to act in like manner as long as the electric current is turned on. The coils 1, ratchet 27, bearings 3 and 26 are all mounted on a base 33 so

that they are electrically insulated from each other.

What I claim and desire to secure by Letters Patent, is—

- 5 1. In an electric motor, a ratchet wheel provided with conducting teeth, the adjacent teeth being insulated from each other, each tooth being electrically connected with a tooth on the opposite side of the wheel, a
- 10 magnet, a conducting lever arranged to be actuated thereby, a conducting pawl pivotally connected to said lever and arranged to engage the teeth of the ratchet successively, a second conducting pawl on the opposite side of said ratchet wheel arranged to engage the teeth of the ratchet, a source of current, electrical connections between said source of current and said magnet and between said magnet and said lever, and
- 15 electrical connections between said source of current and said second named pawl, the movement of one of said pawls serving to break the electric circuit.
- 20 2. In an electric motor, a ratchet wheel comprising an insulating body, conducting teeth disposed around the periphery of said body, a pair of conducting rings, electrical connections between alternate teeth and one of said rings, electrical connections between the other of said rings and the remaining teeth, an actuating pawl on one side of said ratchet, a second pawl on the opposite side of said ratchet, said pawls being normally in
- 25 electric connection with each other through the medium of certain of said conducting teeth and one of said conducting rings, electrical connections between
- 30 the other of said rings and the remaining teeth, an actuating pawl on one side of said ratchet, a second pawl on the opposite side of said ratchet, said pawls being normally in
- 35 electric connection with each other through the medium of certain of said conducting

teeth and one of said conducting rings, means for moving the actuating pawl, the movement of the second named pawl from its tooth to the adjacent tooth serving to break the circuit between the two pawls.

40

3. In an electric motor, a ratchet wheel comprising an insulating body, conducting teeth disposed around the periphery of said body, a pair of conducting rings, electrical connections between alternate teeth and one of said rings, electrical connections between the other of said rings and the remaining teeth, an actuating pawl on one side of said ratchet, said actuating pawl being provided with an adjustable conducting spring arranged to engage said teeth, a second pawl on the opposite side of said ratchet, said second pawl being provided with a conducting spring arranged to engage the teeth of said ratchet, said pawls being normally in electrical connection with each other through the medium of certain of said conducting teeth and one of said conducting rings, means for moving the actuating pawl, said means comprising a pivoted lever having an armature at one end and a magnet for said armature, a source of current for said magnet, the movement of the second named pawl from its tooth to the adjacent tooth serving to break the circuit between the two pawls.
